UNITED STATES PATENT OFFICE.

OSKAR FISCHER, OF BERLIN-FRIEDENAU, GERMANY, ASSIGNOR TO N. V. MACHINA MAATSCHAPPIJ VOR HANDEL EN INDUSTRIE, OF AMSTERDAM, HOLLAND, A CORPORATION OF HOLLAND.

FRAME FOR TYPEWRITING MACHINES.

Original application filed January 25, 1924, Serial No. 688,399, and in Germany November 4, 1918. Divided and this application filed April 10, 1925. Serial No. 22,062.

My invention relates to improvements in frames for typewriting machines, and the object of the improvements is to provide a frame which is simple in construction and which can be manufactured at low cost. With this object in view my invention consists in constructing the frame from a top plate and a bottom plate both having cleats or bars secured thereto for bracing the same and connected by pillars of circular or square cross-section, which plates and pillars are in part used for supporting certain parts of the mechanism of the machine.

For the purpose of explaining the invention an example embodying the same has been shown in the accompanying drawings in which the same reference characters have been used in all the views to indicate corresponding parts. In said drawings,

Fig. 1, is a sectional elevation taken on the line 1—1 of Fig. 2 and showing the frame and parts of the mechanism,

Fig. 2, is a sectional plan view of the machine taken on the line 2—2 of Fig. 1,

Fig. 3, is a sectional elevation on an enlarged scale taken on the line 3—3 of Fig. 1 and showing a rail secured to the bottom plate, and

Fig. 4, is a top plan view of the machine with the top part of the paper carriage removed and showing the guide rails for the carriage secured to the top plate.

In the example shown in the drawings the frame of the typewriting machine consists of bottom and top plates 1 and 2 braced by bars 3, 5, 6, 7, 8, 9 and 10 and rails 11 and 12 and connected by pillars 13 to 22 in part of circular and in part of rectangular cross-sections and side and end frame members 23 to 26 and 4, as is shown in Figs. 1 and 2. The frame is supported on a base frame 32 strips 34, 35 of felt or similar sound dampening material being interposed between the bottom plate 1 and the base frame 32. The frame 32 is supported on feet 36, 37 secured to the base frame through the intermediary of leaf springs 38; pieces 39 of felt or the like being interposed between the springs 38 and the frame 32. The feet 36, 37 are provided with pieces 40, 41 of felt or rubber secured to the bottoms thereof. I have

found that by thus mounting the frame of the machine on cushioning members the noise caused by the operation of the operative parts is reduced to a minimum.

The inner parts of the machine are protected as against injury and dust by plates 42 to 45 of glass fitted in the frame members 3, 4, 5, 6, 7 and 8. The pillars 14, 15, 17 and 18 are connected with one another by horizontal braces 27, 28, 29 and 30.

For a better understanding of the invention I shall now briefly describe the manner of mounting the main parts of the mechanism of a typewriting machine on the frame, and I shall make reference to the typewriting machine described in my copending application Ser. No. 688,399 which has matured into Patent 1,553,765, dated Sept. 15, 1925, and of which the present application is a division. But I wish it to be understood that my invention is not limited to the use of the frame in a machine of the type described in the said original application.

To the pillars 17 bearings 67 are secured which provide a support for a plate 68 carrying a type cylinder 53. To the bottom face of the plate 1 pillars 69 are secured on which an electromagnet 70 is mounted the armature 71 of which is connected by a rod 72 with the plate 68, the object of the electromagnet and its armature being to throw the type cylinder against the platen 73. Further, brackets 58 are secured to the bottom face of the plate 1, and on the said brackets a rocker 57 is mounted which is adapted to lift the type cylinder 53 through the intermediary of a rod 59 acting on the bottom end of the stem 61 of the type cylinder 53. The rocker 57 is connected by links 56 with shift key levers 54 mounted on brackets 55 secured to the bottom plate 1. Further, the bottom provides a support for the following members: brackets 52, on which the type key levers 48, 49 are mounted; the bar 9, providing an abutment for rockers 74 carried by the type key levers; brackets 75, from which two rockable frames 84 and 85 are suspended, a rail 76, providing a support for bearing members 78 for levers 77; the transverse bar 10, slotted at its top part, for guiding the rear ends of the levers 77, and

having a bracket 79 secured thereto; angular pieces 80, for mounting an electromagnet 64 on the bottom plate 1; an insulating block 81, carrying one of the terminals of an electric circuit; and blocks 82 and 83, supporting a circuit make-and-break device. On the pillars 21 and 22 a rockable frame 86 is mounted which carries the armature 65 of the electromagnet 64 and other parts. To 10 the bottom face of the rail 4 a horizontal plate 47 is secured on which the tabulation keys 46 are mounted. The rails 11 and 12 secured to the top plate 2 provide guide ways for the paper carriage 50. To the top 15 plates other parts are secured which, however, will not be described in detail.

Since my invention relates only to the construction of the frame I deem it not necessary to describe the mechanisms mounted 20 thereon in detail.

My improved frame is simple and rigid in construction. Since all the parts of the frame are accessible all the mechanisms can be readily mounted thereon. The cost of the 25 manufacture is low, because all the parts are simple in construction, and can be manufactured independently of each other and before being assembled. In the construction of the frame the top and bottom plates are cut 30 from sheet metal, and all the bores are exactly drilled by means of patterns. Many parts of the mechanism of the machine are directly mounted on the said plates, and others are secured to the pillars and horizontal 35 braces, which may be provided with the necessary bores, brackets or bearing blocks before being assembled. It will be understood that this mode of manufacturing the frame is less expensive than the manufacture of a cast 40 iron frame in which drilling and other work must be done in the complete frame in which the parts are not always accessible and which must be successively placed on many machine tools. The pillars, bars and plates 45 used in the manufacture of my improved frame are supplied by the market, and they

are sufficiently exact in form so that no finishing work is needed. Further, the said parts are particularly suitable for a manufacture on a large scale, and the work may 50 be done by a large number of workmen. Finally the assembling of the machine may be done by sections, and most of the work may be done by unlearned workmen.

I claim:

1. A frame for typewriting machines, comprising a top plate, a bottom plate, vertical pillars secured to said plates for connecting the same, rails constituting paper-carriage guideways borne by the top plate, 60 and frame members to which said plates are at their edges secured.

2. A frame for typewriting machines, comprising a top plate, a bottom plate, vertical pillars secured to said plates for connecting the same, rails constituting paper-carriage guideways borne by the top plate, 65 frame members to which said plates are at their edges secured, and panels seated in said frame members.

3. A typewriting machine, comprising a frame and the writing mechanism, said frame comprising a top plate and a bottom plate, vertical pillars connecting said plates, and frame members to which the said plates 75 are at their edges secured, the parts of the writing mechanism being mounted on said plates, rods, and frame members.

4. A frame for typewriting machines, comprising a base frame yieldingly borne 80 upon supporting feet, and a bottom plate resting upon cushions upon said base frame, pillars borne by said bottom plate both upon its upper side and upon its lower side, a platen-bearing top plate borne by certain of 85 the said upper pillars, a type cylinder pivotally borne by other of said upper pillars, and a type-cylinder-operating electromagnet borne by said lower pillars.

In testimony whereof I hereunto affix my 90 signature.

OSKAR FISCHER.
